(57) **CLAIM**

The ornamental design for a piano-shaped animal tank, as shown and described.

DESCRIPTION

FIG. 1 is a perspective view of piano-shaped animal tank showing our new design attached to a piano.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

In the drawings, the broken line showing of a piano-shaped animal tank depicts unclaimed environmental subject matter.
